[57] CLAIM

The ornamental design for a liquid applicator, as shown
and described.

DESCRIPTION

FIG. 1 is a perspective view of the liquid applicator,
showing my new design;

FIG. 2 is a top plan view thereof;

FIG. 3 is a bottom plan view thereof;

FIG. 4 is a front elevational view thereof;

FIG. 5 is a rear elevational view thereof; and

FIG. 6 is a side elevational view thereof.

The broken line disclosure of a handle in the drawings
is for illustrative purposes only and forms no part of the
claimed design.
